UNITED STATES PATENT OFFICE.

WILLIAM McCABE, OF ST. LOUIS, MISSOURI.

CORSET OR WAIST.

1,123,907.

Specification of Letters Patent.

Patented Jan. 5, 1915.

Application filed November 16, 1911. Serial No. 660,699.

To all whom it may concern:

Be it known that I, WILLIAM McCABE, a citizen of the United States of America, residing in the city of St. Louis and State of Missouri, have invented certain new and useful Improvements in Corsets or Waists, of which the following is a specification.

For the purpose of creating a neat and dressy appearance in the apparel of women, it is of prime importance to obviate, as far as possible, all undesirable fullness, and any unnecessary parts in connection with the corset or waist. I am well aware that various devices have been employed for padding the fronts of corsets and for supporting the abdomen independently of the corset front, in order to leave the corset free to impart the desired form to the clothing. But these devices have proven unsatisfactory by reason of an undesirable accumulation of goods in the front which seriously impairs a dressy appearance. To obviate these drawbacks forms the primary object of this invention. In attaining this object, my invention contemplates the provision of means whereby that portion of the corset or waist, which is below the waist line, can be taken up or reduced in girth independently of the usual means for drawing the parts of the corset together at the back. With this object in view, I provide an adjustable connection between the rear edges of the front panels of the corset which extends around the back of the wearer within the corset.

A collateral object of my invention is to provide an improved construction for the sides and back of a corset provided with my device which will adapt the corset to fit snugly, and to set properly, whatever the adjustment may be of the take-up device.

Other and further objects will appear in the specification and be specifically pointed out in the appended claim reference being had to the accompanying drawings exemplifying the invention, and in which,

Figure 1 is an inside elevation of a corset provided with my improvements, and opened up from the rear to better display the same. Fig. 2 is a view showing the corset as applied to the wearer, the back of the corset being opened up to show the method of applying my improved device.

Referring more particularly to the draw-

ings, my invention is disclosed as embodied in a corset comprising a pair of front panels 55 1 which may be detachably connected together in any well-known manner (not shown), such as the usual clasp fastenings, a back panel 2, spaced from each front panel and connected thereto by an insertion to be 60 described presently. The back panels are provided with holes 3 for the usual lacing (not shown in the drawings). For connecting each front panel 1 to its corresponding back panel 2, I provide an insertion consisting of an inextensible strip 4 at the upper end of the corset, and a plurality of elastic straps 5 at the lower end, which coöperate with the girth reducing device now to be described, by imparting elasticity to the lower 70 portion of the corset to adapt it to conform readily outside of the girth reducing device in the rear.

In order to provide an adjustable connection between the front panels 1 around the 75 back of the corset, I preferably secure a wing 6 to the rear edge of each of said panels adjacent the lower end thereof, securing to one of these wings a buckle 7 and to the other a strap 8 which could, of course, 80 be replaced by any other suitable fasteners without departing from the spirit of my invention.

The use of my improved device will now be readily understood. To secure the desired support for the abdomen, and at the same time to draw the front panels close in to the body of the wearer and toward the rear, the strap 8 is adjusted through the buckle 7 until the desired tension is secured. 90 By an inspection of Figs. 1 and 2, it will be seen that this device forms, with the lower ends of the front panels 1, an adjustable inextensible band, the back panels being adapted to be secured together independently on the outside with the elastic straps 5 drawing the corset or waist proper snugly about the person of the wearer. While the insertion can be made entirely inelastic or entirely elastic, I prefer to embody my invention in the particular form shown in the drawings.

What I claim is:

A corset comprising a pair of front panels, a back panel secured to each of said 105 front panels, a wing secured to the rear

edge of the lower portion of said front panels, means for drawing and fastening said wings together, said front panels and said wings forming an adjustable inextensible band, said back panels adapted to be laid over said wings after said wings have been drawn together, and extensible strips se-

cured between said front and rear panels for allowing said rear panels to be self-adjusting over said wings.

WILLIAM McCABE.

In the presence of—

M. C. HAMMON,

H. G. FLETCHER.
